UNITED STATES PATENT OFFICE.

LAWRENCE H. BARRY, OF CALDWELL, OHIO.

FENCE-POST.

SPECIFICATION forming part of Letters Patent No. 674,231, dated May 14, 1901.

Application filed October 30, 1900. Serial No. 34,950. (No model.)

To all whom it may concern:

Be it known that I, LAWRENCE H. BARRY, a citizen of the United States, residing at Caldwell, in the county of Noble and State of Ohio, 5 have invented a new and useful Fence-Post, of which the following is a specification.

The invention relates to improvements in fence-posts.

The object of the present invention is to 10 improve the construction of fence-posts and to provide a practically indestructible one designed to be constructed of burnt clay or other suitable material and adapted to permit fence-wires to be stapled or otherwise se- 15 cured to it.

The invention consists in the construction and novel combination and arrangement of parts hereinafter fully described, illustrated in the accompanying drawings, and pointed 20 out in the claim hereto appended.

In the drawings, Figure 1 is a perspective view of a fence-post constructed in accordance with this invention and illustrating the manner of stapling fence-wires to it. Fig. 2 25 is a vertical sectional view of the same. Fig. 3 is a similar view illustrating another means for attaching the fence-wires. Fig. 4 is a horizontal sectional view on the line xx of Fig. 2. Fig. 5 is a detail view of the fence-post, illus- 30 trating the arrangement of the perforations.

Like numerals of reference designate corresponding parts in all the figures of the drawings.

1 designates a hollow tapering fence-post 35 designed to be constructed of burnt clay or any other suitable material, and the said post, which is preferably rectangular in horizontal section, as illustrated in Fig. 4 of the accompanying drawings, is designed especially for 40 use in connection with wire fences, and in order to enable the wires to be readily secured to it it is provided with groups of perforations 2 and 3. The fence-post is not subject to decay and is practically unaffected by the 45 weather, and the perforations 2 and 3 are arranged in pairs. The perforations 2 are horizontally alined and are adapted to receive a horizontal tie 4, which passes through the fence-post from front to rear and which em- 50 braces and binds a wooden strip 5 to the front

of the post. The ends of the wire are preferably twisted at the back of the post, as clearly shown in Fig. 2. The wooden strip, which may be of any desired length, terminates short of the ground, and the wire ties 55 may be arranged at any desired intervals. The wires 6 are secured to the wooden strip by staples 7, which are adapted to be driven into the said wooden strip at any desired point, whereby the horizontal fence-wires may 60 be arranged at any desired elevation and may be secured to the fence-post 1 with the same facility that they can be secured to an ordinary wooden post.

Instead of securing the horizontal fence-wires to the fence-post by means of staples and the wooden strip the wires may be fastened directly to the post by means of wire ties 8, consisting of loops having their sides extended through the perforations 3 from the 65 front of the post to the back thereof. The perforations 3 are vertically alined, and the wire of the tie 8 is doubled to form an eye 9 at the front of the post for the reception of the horizontal fence-wires, which are arranged 70 as clearly illustrated in Fig. 3 of the accompanying drawings. The perforations 2 and 3 are formed in both the front and back of the post, and the wire ties extend across the space inclosed by the walls of the said post, 75 as clearly shown in Fig. 4. The front of the post is provided with transverse grooves 10, located in alinement with the horizontally-alined perforations and adapted to receive a fence-wire when the latter is secured directly 80 to the fence-post.

It will be seen that the fence-post is practically indestructible, that it is adapted to be manufactured of burnt clay and analogous material, and that it will enable fence-wires 85 to be readily connected to it. It will also be clear that wood railings or any other form of fencing may be secured to the post when the wooden strip is employed. Also instead of making the post tapered it may be of the same 90 diameter throughout its entire length.

What I claim is—

As a new article of manufacture, a hollow plastic fence-post, rectangular in cross-section provided at its front and back with reg- 95 100

istering groups of perforations, each group consisting of a pair of vertically-aligned perforations and a pair of horizontally-aligned perforations adapted to receive a wire tie and capable of permitting the same to be arranged either in a vertical or a horizontal position for securing a fence-wire or a wooden strip to the fence-post, said post being also provided at its front with horizontal grooves arranged in the same plane as the horizontally-aligned

perforations and adapted to receive horizontal fence-wires, substantially as described.

In testimony that I claim the foregoing as my own I have hereto affixed my signature in the presence of two witnesses.

LAWRENCE H. BARRY.
